UNITED STATES PATENT OFFICE.

EDWARD W. JEWELL, OF CHICAGO, ILLINOIS.

DESIGN FOR A CASING FOR ELECTRICAL METERS.

SPECIFICATION forming part of Design No. 34,800, dated July 16, 1901.

Application filed May 24, 1899. Serial No. 717,984. Term of patent 14 years.

To all whom it may concern:

Be it known that I, EDWARD W. JEWELL, a citizen of the United States, residing at Chicago, in the county of Cook and State of Illinois, have invented and produced a new and original Design for the Casing of an Electrical Meter, of which the following is a specification, reference being had to the accompanying drawing, forming part thereof.

10 My design is illustrated in the accompanying drawing.

The casing a , which is cylindrical in form is mounted upon a base a' , which is of somewhat larger diameter and the periphery of which is 15 rounded, as shown. At the upper end of the casing a a band a^2 , of slightly larger diameter, is provided, and at the upper edge of this a beaded portion or rim a^3 is mounted. Within the casing and at a distance from the upper edge thereof an annular portion or plate

b is provided, having at the center a circular opening b' .

The essential feature of the design is the cylindrical casing with the parts associated therewith, substantially as above described, 25 and having the annular portion b mounted on the upper end thereof and provided with the central circular opening.

Having described my invention, what I claim as new, and desire to secure by Letters 30 Patent, is—

The design for the casing of an electrical meter, substantially as described.

In witness whereof I have hereunto subscribed my name in the presence of two witnesses. 35

EDWARD W. JEWELL.
